UNITED STATES PATENT OFFICE.

CARL R. MILLER, OF ALVARADO, MINNESOTA.

COMBINED LADDER AND BOARD.

Application filed June 12, 1925. Serial No. 36,691.

My present invention has reference to a combined step ladder and ironing table.

The object is the provision of a device of this character in which the supporting legs 5 for the ladder are made up of pivotally associated sections whereby the outer leg sections may be swung angularly over the sides of the ladder and secured thereto in a novel manner so that the inner legs will 10 provide a support for a removable ironing board, the top of the ladder having a cleat for engaging the inner edge of the said board.

A further object is the construction of a 15 device for this purpose in which the elements constituting the same are effectively braced when set up as a step ladder or when folded to provide an ironing board support.

20 A still further object is the provision of a device for this purpose that is characteristic of simplicity in construction, cheapness in manufacture and thorough efficiency for the purpose devised.

25 The drawings illustrate a satisfactory embodiment of my improvement reduced to practice.

In the drawings:

Figure 1 is a rear elevation of the improvement set up as a step ladder.

Figure 2 is a section on line 2-2 of Figure 1.

Figure 3 is a top plan view thereof.

Figure 4 is a plan view of the device 35 set up to support an ironing board.

Figure 5 is a sectional view approximately on the line 5-5 of Figure 4.

The step ladder portion 1 of the improvement is of the ordinary construction, the 40 side elements of which are braced, as at 2 and 3, adjacent to the bottom and adjacent to the top portions thereof. The braces 2 are in the nature of metal straps secured between the sides and the lower step of the 45 ladder while the brace 3 is in the nature of a wooden strip that is also secured to the top or upper step portion 4 of the ladder. The top 4 has depending sides 5 having a depending transversely arranged cleat 6 be-

50 tween the said sides at the outer edge of the said top 4. The step of the ladder, next to that provided by the top 4 has secured on its under face an eye 7, and the side members of the ladder portion 1, below the eye 55 7, are provided with oppositely disposed substantially L-shaped spring clamps 8. Below

the clamps 8 there is secured to one of the steps of the ladder, through the medium of an eye 9, a rod 10 which has its free end hooked, as at 11. The supporting legs for 60 the ladder include an upper section 12 and a lower section 13. The upper section has its side members pivotally secured, as at 14, to the sides 5 of the top 4. The side members of the lower section, at their points of 65 contact with the sides of the upper section 12, are cut obliquely, and are pivoted to the sides of the said section 12 by means 15. The supporting legs have transversely arranged cleats 16 and 17 designed for lapping 70 relation when the leg sections 12 and 13 are in alignment. These cleats have central openings therethrough for the reception of the hooked end of the spacer rod 10. This effectively holds the supporting legs in proper spaced relation to the step ladder portion 1 of the improvement. As the leg portions 13 are disposed a greater distance away from each other at their outer than at their inner 75 pivoted ends a comparatively broad brace is 80 afforded the construction so that the liability of the tilting thereof will be avoided.

There is pivotally connected between the side members of the leg section 12 the side members of a pail holding shelf 18. This shelf, when not in use, is swung between the said sides of the leg section 12 and contacts with a round 19 between the side members of the said leg section.

When the device is to be set up as a support for an ironing board, the spacer rod 10 has its hooked end removed from engagement with the cleats 16 and 17, and swung to engage the eye 7. The legs of the outer leg section 13 are swung on their pivots 15 to 90 straddle the sides of the ladder portion 1. This brings the cleat 17 of the leg section 13 to engage with the spring clamps 8, so that the device is held in the position illustrated in Figures 4 and 5 of the drawings. A removable ironing board 20 is arranged over the leg section 12 and has one of its ends also brought to engage between the said leg section and the cleat 6. The cleat 16 is 95 braced, as at 21, to the side member of the leg section 12 and the construction is such that the ironing board will be firmly supported, there being, of course, a binding engagement between the side members of the leg section 12, and the under face of the 100 ironing board to force the latter into frictional contact with the cleat 6. This pres-

sure is released when the leg section 13 is swung out of engagement with the clamps 8. When not in use the step ladder portion will be swung against the leg portions 12 and 13, in which instance, of course, the pail holding shelf is swung between the side members of the leg section 12 so that the device presents a small package when not required for use.

Having described the invention, I claim:

A step ladder having a top, provided with depending sides and a transverse depending cleat, legs pivotally secured to the sides of the top, inward of the cleat, said legs each comprising two pivotally associated sections, the inner walls of the outer sections, at their pivotal connections with the upper sections,

being beveled, transverse bars on the leg sections designed for lapping engagement 20 when the sections are in alignment and said bars having aligning openings therethrough, a hook carrying rod hung from the ladder and designed to have its hooked end passed through the openings for holding the leg 25 sections in alignment, said outer leg sections arranged to swing over the sides of the ladder, hook-like spring clamps on the sides of the ladder to engage with the referred to bar on the outer leg sections, and said outer 30 leg sections, when so engaged, designed to swing the pivoted end of the inner leg sections toward the cleat to clamp an element between said leg sections and said cleat.

In testimony whereof I affix my signature.
CARL R. MILLER.
